UNITED STATES PATENT OFFICE.

JOHN L. FORD, OF CAMDEN, NEW JERSEY.

BRUSH-HANDLE.

1,073,034.

Specification of Letters Patent. Patented Sept. 9, 1913.

Application filed March 21, 1913. Serial No. 755,971.

To all whom it may concern:

Be it known that I, JOHN L. FORD, a citizen of the United States, residing at Camden, in the county of Camden and State of New Jersey, have invented new and useful Improvements in Brush-Handles, of which the following is a specification.

This invention relates to brush handles; and it has for its object the provision of a handle of this character which may be adjusted to different positions upon the brush head and arranged thereon so that when a particular surface of the head is worn the head may be quickly adjusted so as to expose a new surface.

Another object of the invention is the provision of a handle which may be securely connected with the head and positively held against lateral movements thereon while the brush is in use.

Another object of the invention is the provision of a brush handle which may be used in connection with a brush head having angularly disposed surfaces which are adapted to mutually assist in the action of similar surfaces of the handle and thereby effect a secure connection between the handle and the head.

With these and other objects in view, the invention consists of certain novel features of construction, combination and arrangement of parts, as will be hereinafter described and claimed.

In the accompanying drawings:—Figure 1 is a perspective view of the handle, showing the application of the same to a rectangular brush head; Fig. 2 is a top plan view; and Fig. 3 is a side view, showing parts in section.

While it is to be understood that the handle is to be used in connection with a brush head of any suitable configuration where angularly-disposed side surfaces will be presented, it is described that the brush head A illustrated herein is of rectangular configuration, so as to present straight angularly-disposed side surfaces B. The head as designed herein is provided with bristles C, which may be of any suitable well known construction.

The handle 1 is provided with a horizontally-disposed gripping portion 2 which terminates in an angularly disposed branch 3 having an integral flange arm 4, which is preferably disposed in parallel relation with

the gripping portion 2 and arranged to lie in mutual contact with the upper flat surface of the head A. The branch 3 is provided with depending flanges 5 which are collectively associated in substantially V-form, so as to accommodate themselves to adjacent surfaces B of the brush head at any corner of the latter. In this manner it is evident that when the flanges 5 are engaged against two adjacent surfaces B of the head, the handle will be securely held against lateral movements.

The arm 4 is provided with an elongated slot 6, and as illustrated the brush head is provided with a centrally located screw 7 having a flat washer 8 thereon and a clamping winged nut 9, the latter being disposed above the arm 4 as illustrated. The screw 7 rises from the head A being extended through the slot 6 of the arm 4 and arranged so that the handle may be slidably moved across the head A and then rotated around the axis of the screw 7 and then subsequently adjusted at any desired corner of the head A so as to bring the flanges 5 of the branch 3 into mutual contact with two adjacent surfaces B of the brush head. After this operation, the winged nut 9 may be adjusted to a clamped position so as to force the under surface of the arm 4 in effective frictional contact with the upper surface of the head A. The brush head is then securely held in place upon the handle and the latter is positively held against movements in any direction.

Now that the details of construction of the device are clearly described, it is seen that when one corner of the bristle surface C is worn, the head A may be adjusted, so as to expose a new surface, and, as a consequence, all of the corner surfaces may in time be presented, so that the bristle surface may be preserved and the brush thereby made to wear equally throughout the length of the bristles.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as claimed.

Having thus described my invention, what I claim is:

A brush handle provided with angularly disposed flanges for engagement with the sides of a brush back and a slotted extension for engagement with the top of the brush back, the slot being adapted for the reception of clamping means so as to hold

the handle in applied position on the brush back.

In testimony whereof I affix my signature in presence of two witnesses.

JOHN L. FORD.
